ROTARY PUMP

Filed April 13, 1936

UNITED STATES PATENT OFFICE

2,131,302

ROTARY PUMP

Otto C. Selle, Denver, Colo.

Application April 13, 1936, Serial No. 74,083

2 Claims. (Cl. 103—89)

My invention relates to rotary pumps, and it is a primary object of the invention to provide a mechanism in which a given volume of displaced fluid will be moved from an inlet and expelled through an outlet in one complete revolution of the fluid.

Another object of the invention is the provision of machined co-acting housing and runner surfaces to provide a substantially fluid-tight zone whose only entrance is the inlet of the housing and whose only outlet is the housing outlet.

A further object of the invention resides in the provision of a rotary pump which is simple, durable and efficient.

Still another object of the invention is the provision of means cooperating with the pump runner to accelerate the movement of material between the inlet and the runner.

A still further object of the invention is to provide a sealed passage for fluid between the inlet and the outlet in order to prevent any appreciable movement of fluid, other than a progressive movement from inlet to outlet.

Other objects reside in novel details of construction and in novel combinations and arrangements of parts as will more fully appear in the course of the following description.

To promote a better understanding of the invention, reference will now be made to the accompanying drawing in the several views of which like parts have been similarly designated, and in which:

Figure 1 represents a side elevation, partially in section, of apparatus embodying the present invention.

Figure 2 is a side elevation shown partially in section in the approximate position of the line 2—2, Figure 1, and

Figure 3 is a section taken along the line 3—3, Figure 1.

In the drawing, the pump has been illustrated as comprising a housing 4, preferably of cylindrical shape, having an inlet 5 in its bottom. A cylindrical bearing 6 extends upwardly from the bottom of housing 4 and terminates at the bottom of a chamber 4a in the upper portion of the housing, in which the pump-rotor operates.

The housing 4 is flanged as indicated at 7, and a cover plate 8 is fitted on the flanged end 7 of the housing and held against relative movement thereon by suitable fastening means, such as screws 9, while a gasket 10 is held between housing 4 and cover 8 to prevent leakage.

The outlet of the pump is provided in cover plate 8 in alignment with a nipple 12 extending

outwardly therefrom and having interior threads as indicated at 13 for connection with a pipe or conduit (not shown).

When the cover 8 is in place on housing 4, the outlet-and-inlet openings are in vertical alignment.

A shaft 14 extends through cover 8 and carries at its end within the chamber 4a of housing 4, a rotor or pump-runner 15. A suitable stuffing box 16 may be provided to prevent leakage around shaft 14.

The runner 15 comprises a hub 15a provided with a reduced extension 15b which holds the end of the shaft 14 and extends into bearing 6, and a plurality of radially ranging diagonally slanting vanes 15c are carried on the hub for acting on fluent material in the pump.

A set screw 16a or other suitable means may be provided for holding the runner against relative movement on shaft 14 within the housing 4.

The bearing 6 defines an annular passage 17 for material admitted through the inlet 5, and a wall or partition 18 extends across the passage at an inclination from one side of inlet 5 and over the same to the plane of the upper end of bearing 6, at the bottom of the rotor-chamber 4a.

The partition thus acts as a hood for the inlet 5 to prevent return of material thereto, as well as directing displaced fluid through the passage 17. The fluent matter upon reaching the inclined surface of partition 18 in its circulatory course, is thrust laterally by contact therewith, into the sphere of influence of the runner 15 within the chamber 4a.

The shaft 14 is driven by any suitable means and in Figure 1 is illustrated as carrying a pulley 19 driven by a belt 20 attached to a suitable driving element (not shown).

Intermediate the pulley 19 and the pump housing 4, the shaft 14 is encased in a housing 21 provided at both ends with suitable bearings 22 for the shaft, and containing a lubricant chamber. Suitable lubricant is periodically introduced into this chamber through one or more valves 23. Packing glands 34 may be provided as needed to prevent escape of the lubricant along shaft 14. The bearings 22 are contained in screw-caps 21c at opposite ends of the housing 21 and the lowermost cap is formed integral with the cover plate 8 by means of legs 21a.

The operation of the above described pump contemplates movement of a given quantity of fluid inducted through inlet 5, completely through passage 17 and into outlet 12 in one complete revolution.

To this end, the upper end of bearing 6 and the adjoining surface 18a of partition 18 are machined to provide an even surface over which the vanes 15c and the hub 15a rotate. The lower edges 15d of the vanes and the hub are likewise machined and thereby disposed in fluid-tight contact with the end-surfaces of the relatively stationary bearing 6 and partition 18.

The inner surface of cover plate 8 is recessed 10 as shown at 24, and on the side of outlet 12 forward with respect to the direction of rotation, the plate 8 has a downward projection 25 extending across the top of the annular chamber 42. The surface of the projection 25 is also 15 machined and the upper edges 15c of vanes 15 are likewise machined to contact with the projection in fluid-tight relation thereto.

It will be readily understood that the housing 4 may be provided with legs or other supporting 20 elements if it is to be used for vertical pumping, and placed in a sump or other fluid containing chamber. It is also evident that a suitable conduit may lead from the inlet into a supply of the fluid to be pumped.

In order to accelerate the movement of entering 25 fluids, the passage 17 progressively narrows from inlet 5 to the top of partition 18.

In operation, rotation of runner 15 draws fluent matter through inlet 5 into passage 17 by suction, and the narrowing volume of the passage 30 causes a progressive increase in velocity.

When the displaced fluid strikes the partition 18 it is thrust upwardly into the sphere of influence of vanes 15c of the rotor within the chamber 35 4a. A measured quantity is carried forward by each vane due to the slicing action resulting from the passage of such vane over the surface 18a of partition 18, and is elevated at the same time, due to the diagonally slanting shape of the vane.

At the same instant the fluid is elevated, the upper edge of the blade next forward with relation to the direction of rotation contacts the machined surface of projection 25 and as none of the elevated fluid is free to escape in a forward direction, it, consequently, passes directly 40 into outlet 12.

Another benefit derived from the sealed zone of rotation of runner 15, is the increase in suction 45 derived. As practically no fluid can reach the runner other than by traveling through passage

17 to the upper end of partition 18, the suction effect produced by rotation of the rotor is concentrated in this zone.

By combining the increased suction action with the acceleration due to the decreasing area of 5 the passage, the material admitted through inlet 5 reaches the sphere of action of blades 15c in a relatively brief interval and thereafter is rejected in substantially one-quarter revolution of runner 15.

From the foregoing, it is apparent that the mechanism is simple and durable and will effect an efficient pumping with a relatively low power consumption.

In order to maintain a fluid-tight contact between the upper and lower surfaces of the runner, and the machined faces of the bearing 6, the partition 18a and the projection 25, the thickness of the gasket 10 may be varied and/or the position of the runner on the shaft may be adjusted 20 by loosening the set-screw 16a.

Changes and modifications may be availed of within the spirit and scope of the invention as defined in the hereunto appended claims.

What I claim and desire to secure by Letters 25 Patent is:

1. A rotary pump comprising a cylindrical housing having an axial inlet at one end and an axial outlet at its opposite end, a vaned propeller fitted into the housing adjacent the outlet, an annular inlet chamber in the housing between the inlet and the propeller, and a radial partition extending helically across said inlet chamber from the inlet end thereof to the propeller and being inclined in a direction opposite to the 35 inclination of the propeller vanes, said partition beginning in the inlet end of the housing at one side of the inlet and extending across the inlet to its end adjacent the propeller.

2. A rotary pump comprising a cylindrical 40 housing having an inlet and an outlet in axial alignment, a vaned propeller positioned in the housing adjacent the outlet, an annular inlet chamber in the housing between the inlet port and the propeller and axially open to the propeller, and a helical partition in the chamber preventing direct axial flow between the inlet and the outlet and inclined in the direction of rotation of the propeller.
